Primary Examiner — Kelley Donnelly(74) *Attorney, Agent, or Firm* — Michael J. Bootcheck,
LLC; Michael Jonathan Bootcheck(57) **CLAIM**

The ornamental design for a pivotable shelf, as shown and described.

DESCRIPTION

FIG. 1 is a perspective view of the pivotable shelf;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof with optional components in phantom lines and not a claimed part of this invention.
